F. W. Howard

W. C. Young.

Inventor;

Michael Callan,
by M. A. Dooley,
Attorney.

UNITED STATES PATENT OFFICE.

MICHAEL CALLAN, JR., OF LYTLE CITY, IOWA.

CHECK-ROWER FOR CORN-PLANTERS.

SPECIFICATION forming part of Letters Patent No. 274,266, dated March 20, 1883.

Application filed October 7, 1882. (No. model.)

To all whom it may concern:

Be it known that I, MICHAEL CALLAN, Jr., a citizen of the United States, residing at Lytle City, in the county of Iowa and State of Iowa, have invented certain new and useful Improvements in Check-Rowers for Corn-Planters; and I do hereby declare the following to be a full, clear, and exact description of the invention, such as will enable others skilled in the art to 10 which it appertains to make and use the same.

The objects of my improvement in check-rowers are to lessen the number of parts and avoid complexity, thus reducing friction; to support the knotted wire or cord independently of the feed-hoppers and other mechanism of the 15 corn-planter, by which many breakages of these parts are avoided; to lessen by one-half the number of knots or trippers usually employed to operate the levers controlling the feed-slide; to prevent the machine from being clogged by dirt, and to improve the construction and operation of the anchor device, by 20 which the chain is easily shifted.

The invention consists of certain parts and 25 combination of parts hereinafter described and claimed.

Referring to the drawings, Figure 1 is a view in side perspective of a planter embodying my improvements, and showing the form and location of the anchor; and Fig. 2 is a side perspective, partly in section, showing the device 30 for operating the seed-slides.

My improvements may be attached to any corn-planter of ordinary construction. I have 35 shown one form of such planter in the drawings, in which—

A A are the side bars, and B, B', and B'' the cross-bars, constituting the frame, which is mounted on the side wheels, 1 2.

40 C C are the seed-hoppers, mounted respectively over the tubes D, which are so arranged as to conduct the grain down into the furrows made by the runners E.

F is the driver's seat, mounted upon cross-bars B and B'.

The devices constituting the check-rower proper are attached to side bars, G, supported about a foot outside of the machine on cross-pieces, which may be extensions of the cross-pieces B B' B'', or consist of other supports 50 extending from the main frame. The bars G

are united at the front by cross-piece 3, which is supported by the tongue, as shown in Fig. 1. These duplicate seed-slide-operating devices mounted on bars G—one on each side of the machine and parallel thereto—operate alternately to carry the chain or cord, which does not cross the machine, as is the case in many planters.

H is a box consisting of two plates, i i, riveted to the opposite sides of bar G, and provided with a lid, j, and a spring-catch, j', to hold the lid closed. The plate i' on the inner side of the bar G is set off from the bar by lugs, (not shown,) to give the box an open bottom, to 60 admit the falling through of dirt. H' is a similarly-constructed box on the opposite end of bar G.

K is one arm of a crank-lever pivoted to the oscillating arm L. It is bent so as to enter 70 the box H, in which it is given a reciprocating motion by the operation of the cord, as herein-after described.

M is a corresponding arm, pivoted to the opposite end of arm L, and reciprocating in 75 the opposite box, H'. Each of these arms is provided with a forked head or crotch, l, and a cross-pin, m', the cross-pin m' moving to and fro in a slot, m''. Each box, also, is provided with a small roller, s', for the purpose herein-after mentioned.

N is an oscillating lever, connected with arm L by pivot h passing through plate o. To the inner end of lever N is attached a rod, n', which connects with a reciprocating bar, R, 85 for operating the seed-slide, through a short arm, Z'.

T is a pulley mounted on the top of a slotted standard, t, which is placed on the forward end of bar G, as shown in Fig. 2, to conduct 90 the chain into the box H and maintain it in a straight line.

X is the chain or cord, provided with knots W at a distance from each other of two rows.

Y is the anchor, consisting of a single bent 95 piece of metal or stout wire, having a loop, y', formed by a single twist of the rod, to which loop the end of the chain is connected, and provided with anchor-pins z z', to which the rod is attached by loops, so that it will turn 100 thereon. The anchor-pins are fixed in the ground in line with the rows. When the end

of a row is reached the chain is shifted to the next row by simply turning over the looped rod. One round is thus planted without shifting the anchor.

The operation of the machine is as follows: As the planter is moved forward the knots W of the chain first come in contact with the crotch b in the end of arm K , which has the effect to carry said arm backward. This motion is communicated to the oscillating levers L and N , which serve, through rod n' , to move laterally the sliding bar R and the seed-slide Z^2 , and thus release a charge of seed from the hopper C . As the knot carries the arm backward the pin m' moves downward in the slot m^2 , thus releasing the knot from the crotch. The knot now strikes the roller s' , and is carried thereby beyond the crotch and the box W . As the machine moves forward the same knot comes in contact with the opposite crotch on the end of the arm M within the box H' . This gives the oscillating arms L and N a motion in the opposite direction, which serves to again move the feed-slide, and the knot is disengaged from the crotch and box by the same mechanism already described as connected with box H . Thus the movement of one knot alone serves to operate the slide of each hopper twice, which operation effects the planting of two hills on each row. At the end of the row the chain is shifted to the other side of the planter by the means already described, and the operation repeated with the duplicated devices on that side of the machine. The lids of the boxes held down by the spring-catch serve to keep the chain and knots in place during their passage. In this machine springs for automatically operating the levers and slide are dispensed with. One-half of the number of knots usually employed is dispensed with, thus making the chain lighter, and reducing to the same extent the friction on the chain and other parts. The chain and its supports are entirely disconnected from the hoppers, being supported mainly by the frame resting upon the tongue, and thereby the breaking and damaging of the hoppers by operation or clogging of chain are avoided. The chain and knots not crossing the machine, all unequal strain on the planter is also avoided.

It will be seen, also, that the apparatus, by the fewness and simplicity of its parts, avoids the friction consequent on the employment of complicated mechanism and admits of quick and easy repair.

Having thus described my invention, what I claim, and desire to secure by Letters Patent, is—

1. In a check-rower, the combination of the front horizontal cross-bar, 3 , supported by the tongue, the boxes H , the reciprocating arms provided with the forked heads and cross-pins, the oscillating levers, the sliding bar, the feed-slide, and the chain, all supported independently of the feed-boxes, and constructed substantially as described.

2. In a check-rower, the box H , through which the chain is carried, consisting of the side plates, $i i'$, provided with a lid, and having an open bottom to permit the dirt to fall through, substantially as described.

3. In a corn-planter, the combination of the side bars supporting the check-row device and the front cross-bar, 3 , resting upon the tongue, whereby the chain and its supports are entirely disconnected from the hoppers and are mainly supported by the tongue, substantially as described.

4. The supporting side bars, G , united at the front end by cross-piece 3 , supported by the tongue, in combination with the guide-wheel T , the reciprocating arms, each provided with forked heads and cross-pin, said pin moving in a slot, m^2 , in box H , and the said box H , provided with roller s' , substantially as and for the purpose described.

5. The anchor Y , consisting of a single piece of bent rod or wire having two arms, the shorter arm and the loop y^2 formed by a single twist of the rod or wire, and provided with the stakes-pins $z z'$, attached thereto, substantially as described.

In testimony whereof I affix my signature in presence of two witnesses.

MICHAEL CALLAN, JR.
